UNITED STATES PATENT OFFICE.

ROBERT S. WRIGHT, OF SOMERVILLE, MASSACHUSETTS.

DESIGN FOR A COUCH, LOUNGE, OR SOFA.

SPECIFICATION forming part of Design No. 21,362, dated February 23, 1892.

Application filed December 22, 1890. Serial No. 375,507. Term of patent 14 years.

To all whom it may concern:

Be it known that I, ROBERT S. WRIGHT, of Somerville, in the county of Middlesex and State of Massachusetts, have invented and 5 produced a new and original Design for a Couch, Lounge, or Sofa, of which the following, taken in connection with the accompanying drawing, is a specification.

The drawing is a perspective view of a 10 couch, lounge, or sofa, showing my design.

The leading feature of my design is the head-section at an angle to the body of the lounge and the side rails of the frame prolonged beneath the head-section in drooping 15 extensions terminating near the floor.

A is the body or frame of the lounge, couch, or sofa, B the head-section, and C C the drooping extensions of the side rails of the frame.

Duplicate open triangles with curved lower 20 sides are formed by the head-section B, the

extensions C C, and the oblique rods E E, as shown. The frame and head-section are properly upholstered, and, with the legs and drooping extensions, are suitably finished and ornamented.

The peculiar effect of the drooping extensions C C beneath the head-section B is characteristic of my design and is not materially affected by the ornamentation of the parts.

What I claim is—

The design for a couch, lounge, or sofa, herein shown and described.

In testimony whereof I have signed my name to this specification, in the presence of two subscribing witnesses, on this 18th day of December, A. D. 1890.

ROBERT S. WRIGHT.

Witnesses:

A. H. SPENCER,
JAS. P. PRINCE.
